DESIGN FOR A MAGNETO OF FLANGE MOUNTING TYPE

Edward A. Vogel, Beloit, Wis., assignor to Fairbanks, Morse & Co., Chicago, Ill., a corporation of Illinois

Application May 29, 1942, Serial No. 107,049

Term of patent 3½ years

To all whom it may concern:

Be it known that I, Edward A. Vogel, a citizen of the United States, residing in the city of Beloit, county of Rock, and State of Wisconsin, have invented a new, original, and ornamental Design for a Magneto of Flange Mounting Type, of which the following is a specification, reference being had to the accompanying drawing, forming a part thereof.

In the drawing:

Fig. 1 is a top plan view of the magneto of flange mounting type showing my new design; Fig. 2 is a longitudinal side elevation thereof;

Fig. 3 is a bottom plan view of the magneto; Fig. 4 is an end elevation, as viewed from the impulse coupling end of the magneto, and Fig. 5 is an end elevation at the opposite or distributor end thereof. The side elevation opposite that shown by Fig. 2, corresponds in all important respects to the view of Fig. 2.

I claim:

The ornamental design for a magneto of flange mounting type, substantially as shown and described.

EDWARD A. VOGEL.
